(57) **ABSTRACT**

A projecting decoration comprises an outer shell, a light assembly, a light-blocking cover and a controller. The light assembly is mounted inside the outer shell. The light-blocking cover is mounted at the light assembly and has multiple hollowed-out graphic portions, which respectively correspond to multiple light units of the light assembly. The controller is electrically connected to and controls each light unit to emit light, which passes through corresponding hollowed-out graphic portion of the light-blocking cover to light up and project a projected figure to the outer shell. Because the controller controls a part of the multiple light units to turn on and another part to turn off, the outer shell shows various projected figures of different hollowed-out graphic portions corresponding to different light units, thereby enhancing a decorative effect of projecting decoration and inciting a sense of surprise and fun.

PROJECTING DECORATION

BACKGROUND OF THE INVENTION

1. Field of the Invention

The present invention relates to a projecting decoration, especially to a decoration having an outer shell with a light assembly and a light-blocking cover mounted inside. When the light assembly emits light, the light passes through the light-blocking cover to project projected figures to the outer shell and light up the outer shell for decorating.

2. Description of Related Art

With the improvement of life quality, people pay more attention to the festive atmosphere. Hence, decorations are introduced to enhance the ambience and aesthetically appeal of the environment.

Among different decorations, there is one kind of lighting decoration that has a light assembly mounted inside a shaped body. The light assembly lights up the lighting decoration, via the shaped body, making the lighting decoration have a more decorative look than a normal decoration.

However, either when the light assembly is turned on or turned off, the visual appeal of the lighting decoration is decided by the shaped body. In other words, there is no big difference between the looks of the lighting decoration when lit up and when not lit up. Therefore, the lighting decoration lacks variations and surprise and still has insufficient decorative effect.

Another kind of the lighting decoration further has a film with patterns mounted inside the shaped body. The light assembly emits light to the film to project a projected figure on a surface of the shaped body. However, a contour of the projected figure is often blurry and unclear, and therefore the lighting decoration still has poor decorative effect needing to be improved.

SUMMARY OF THE INVENTION

The technical issue that a projecting decoration in accordance with the present invention resolves is that there is no big difference between looks of a conventional lighting decoration when turned on and when turned off, therefore lacking variations, surprise and decorative effect, or a contour of a projected figure on a lighting decoration is often blurry and unclear.

The projecting decoration of the present invention comprises an outer shell, a light assembly, a light-blocking cover, and a controller. The outer shell is hollow internally and allows light to pass through. The light assembly is mounted inside the outer shell and comprises a base board and multiple light units mounted at the base board and being controllable to emit light. The light-blocking cover is mounted inside the outer shell, is mounted at the base board, and comprises a light-blocking body and at least one separating wall. The light-blocking body is hollow, is connected to the base board of the light assembly, and has multiple hollowed-out graphic portions, which respectively correspond to the multiple light units. The at least one separating wall is mounted inside the light-blocking body and is disposed between each adjacent two of the multiple hollowed-out graphic portions. The controller is electrically connected to the light assembly and controls a part of the multiple light units to turn on while turning off another part of the multiple light units. The controller controls each one

2

of the multiple light units to turn off or turn on, such that each one of the multiple light units emits light to a corresponding one of the multiple hollowed-out graphic portions. The light passes through said hollowed-out graphic portion to project to the outer shell, such that a projected FIG. corresponding to said hollowed-out graphic portion is shown on the outer shell.

The light assembly and the light-blocking cover are mounted inside the outer shell. The controller controls the multiple light units of the light assembly to emit light, so that the light passes through the multiple hollowed-out graphic portions of the light-blocking cover to project the projected figures on the outer shell and at the same time lights up the outer shell. The projecting decoration thereby generates a decorative effect. Especially, the multiple hollowed-out graphic portions show emotive-glowing figures on the outer shell of the projecting decoration. In addition, because the multiple hollowed-out graphic portions are separated by the at least one separating wall, the lights projected to the corresponding hollowed-out graphic portion by two adjacent light units will reduce or avoid the interference with each other. Furthermore, a whole projected figure is divided into parts composed by multiple projected figures, which are respectively projected by the multiple hollowed-out graphic portions and the multiple light units. So, each one of the multiple projected figures has a smaller area with more concentrated light, thereby preventing a contour of the projected figure becoming blurry and unclear. And thus, the whole projected figure shown on the outer shell is clear.

Besides, when the controller controls the multiple light units to turn off, a look of the projecting decoration is only a shape of the outer shell. Alternatively, when the controller controls the multiple light units to turn on, the projected figures of the multiple hollowed-out graphic portions corresponding to the multiple light units will be shown on the outer shell. As a result, the visual appeals of the projecting decoration when turned on and when turned off are significantly different, thereby inciting a sense of surprise and fun and enhancing a decorative effect.

Moreover, the controller can control a part of the multiple light units to turn on while controlling another part to turn off, so that different projected figures of the multiple hollowed-out graphic portions corresponding to different light units are shown on the outer shell. With the multiple hollowed-out graphic portions having different graphics, various projected figures are shown on the outer shell. When the controller repeatedly controls the originally-turned-on light unit to turn off while controlling the originally-turned-off light unit to turn on, the outer shell will continuously show various projected figures, which is similar to animations, thereby inciting a sense of surprise and fun and enhancing the decorative effect.

BRIEF DESCRIPTION OF THE DRAWINGS

FIG. 1 is a perspective view of a first embodiment of a projecting decoration in accordance with the present invention;

FIG. 2 is an exploded perspective view of the first embodiment of the projecting decoration in FIG. 1;

FIG. 3 is an exploded perspective view of a light assembly and a light-blocking cover of the first embodiment of the projecting decoration in FIG. 1;

FIG. 4 is a front view of an interior of an outer shell of the first embodiment of the projecting decoration in FIG. 1;

FIG. 5 is a front sectional view of the light-blocking cover of the first embodiment of the projecting decoration in FIG. 1;

FIG. 6 is a side sectional view of the first embodiment of the projecting decoration in FIG. 1;

FIG. 7 is a front view of the first embodiment of the projecting decoration in FIG. 1, turned off;

FIG. 8 is a front view of the first embodiment of the projecting decoration in FIG. 1, turned on and showing a lighting configuration;

FIG. 9 is a front view of the first embodiment of the projecting decoration in FIG. 1, turned on and showing another lighting configuration;

FIG. 10 is a front view of the outer shell of the first embodiment of the projecting decoration, having at least one painting portion;

FIG. 11 is a front view of multiple said projecting decorations of the first embodiment in FIG. 1, connected together and each having a ground rod;

FIG. 12 is a front view of multiple said projecting decorations of the first embodiment in FIG. 1, connected together and hung up;

FIG. 13 is an exploded perspective view of a second embodiment of the projecting decoration in accordance with the present invention;

FIG. 14 is a front view of the interior of the outer shell of the second embodiment of the projecting decoration in FIG. 13;

FIG. 15 is a front sectional view of the light-blocking cover of the second embodiment of the projecting decoration in FIG. 13;

FIG. 16 is a front view of the second embodiment of the projecting decoration in FIG. 13, turned off;

FIG. 17 is a front view of the second embodiment of the projecting decoration in FIG. 13, turned on and showing a lighting configuration;

FIG. 18 is a front view of the second embodiment of the projecting decoration in FIG. 13, turned on and showing another lighting configuration;

FIG. 19 is a front view of a third embodiment of the projecting decoration in accordance with the present invention, turned on;

FIG. 20 is a front view of the third embodiment of the projecting decoration in FIG. 19, turned off;

FIG. 21 is a perspective view of the light assembly and the light-blocking cover of the third embodiment of the projecting decoration in FIG. 19; and

FIG. 22 is an exploded perspective view of the light assembly and the light-blocking cover of the third embodiment of the projecting decoration in FIG. 19.

DETAILED DESCRIPTION OF THE PREFERRED EMBODIMENT

With reference to drawings and preferable embodiments in accordance with the present invention, descriptions below are to elaborate technical means to achieve intended purpose of the present invention.

With reference to FIGS. 1, 2, 13, and 20, multiple embodiments of a projecting decoration in accordance with the present invention are shown. The projecting decoration comprises an outer shell 10a, 10b, 10c, a light assembly 20, a light-blocking cover 30, and a controller 40.

With reference to FIGS. 2, 13, and 20, the outer shell 10a, 10b, 10c is hollow internally, allowing light to pass through.

With reference to FIGS. 2, 3, 13, and 20, the light assembly 20 is mounted inside the outer shell 10a, 10b, 10c

and comprises a base board 21 and multiple light units 22. The multiple light units 22 are mounted at the base board 21 and are controllable to emit light.

With reference to FIGS. 2 to 5, 13 to 15, 21, and 22, the light-blocking cover 30 is mounted inside the outer shell 10a, 10b, 10c, is mounted at the base board 21 and comprises a light-blocking body 31a, 31b, 31c and at least one separating wall 32. The light-blocking body 31a, 31b, 31c is hollow and has multiple hollowed-out graphic portions 311a to 311j. The at least one separating wall 32 is mounted inside the light-blocking body 31a, 31b, 31c and is disposed between each adjacent two of the multiple hollowed-out graphic portions 311a to 311j. The base board 21 of the light assembly 20 and the light-blocking body 31a, 31b, 31c connect together. The multiple light units 22 respectively correspond to the multiple hollowed-out graphic portions 311a to 311j. Each one of the multiple hollowed-out graphic portions 311a to 311j is at least one hole, which has a preset graphical contour and is formed on the light-blocking body 31a, 31b, 31c.

With reference to FIGS. 11 and 12, the controller 40 is electrically connected to the light assembly 20 and can control each one of the multiple light units 22 to turn on and turn off. Each one of the multiple light units 22 emits light to a corresponding one of the hollowed-out graphic portions 311a to 311j, so that the light passes through said hollowed-out graphic portion 311a to 311j to be projected to the outer shell 10a, 10b, 10c. A projected FIGS. 60a to 60i corresponding to said hollowed-out graphic portion 311a to 311j is hence shown on the outer shell 10a, 10b, 10c. Besides, the controller 40 can control a part of the multiple light units 22 to turn on while turning off another part of the multiple light units 22.

With reference to FIGS. 7 to 9, 11, 12, and 16 to 19, the light assembly 20 and the light-blocking cover 30 are mounted inside the outer shell 10a, 10b, 10c. The controller 40 controls the multiple light units 22 of the light assembly 20 to emit light. The light passes through the multiple hollowed-out graphic portions 311a to 311j of the light-blocking cover 30 to project the projected FIGS. 60a to 60i on the outer shell 10a, 10b, 10c and at the same time lights up the outer shell 10a, 10b, 10c. The projecting decoration thereby generates a decorative effect. Especially, the multiple hollowed-out graphic portions 311a to 311j show emotive-glowing figures on the outer shell 10a, 10b, 10c of the projecting decoration.

Besides, as shown in FIG. 11, the outer shell 10a, 10b can be mounted on a ground rod 70 to be set up on the ground. Alternatively, as shown in FIG. 12, multiple said projecting decorations can be connected together through wires to be hung up under eaves or on a fence. Furthermore, multiple said projecting decorations can be connected together while controlled by the same controller 40 to turn on or off simultaneously, enhancing an atmosphere and lowering down a cost of the controller 40.

Moreover, as shown in FIG. 6, because the multiple hollowed-out graphic portions 311a to 311j are separated by the at least one separating wall 32, the light emitted to one of the multiple hollowed-out graphic portions 311a to 311j by the corresponding light unit 22 will reduce or avoid the interference with the light emitted by another light unit 22. As the light emitted by the multiple light units 22 does not interfere with each other, the outer shell 10a, 10b, 10c will show clear projected FIGS. 60a to 60i. Preferably, as shown in FIGS. 3 and 22, the light-blocking body 31a, 31b, 31c has an assembling opening 312. The base board 21 of the light assembly 20 is mounted at the assembling opening 312 of

the light-blocking body 31a, 31b, 31c. The multiple light units 22 extend into the light-blocking body 31a, 31b, 31c. Each adjacent two of the multiple light units 22 are separated by one of the at least one separating wall 32 to separate the lights emitted by the multiple light units 22, thereby making the projected FIGS. 60a to 60i clearer. In addition, a whole projected figure is divided into parts, composed by multiple projected FIGS. 60a to 60i, which are respectively projected by the multiple hollowed-out graphic portions 311a to 311j and the multiple light units 22. So, each one of the multiple projected FIGS. 60a to 60i has a smaller area with more concentrated light, thereby preventing a contour of the projected FIGS. 60a to 60i becoming blurry and unclear, and thus the whole projected figure shown is clear.

Additionally, as shown in FIGS. 7, 16, and 20, when the controller 40 controls the multiple light units 22 to turn off, a look of the projecting decoration is merely a shape of the outer shell 10a, 10b, 10c. Alternatively, as shown in FIGS. 8, 9, and 17 to 19, when the controller 40 controls the multiple light units 22 to turn on, the projected FIGS. 60a to 60i of the hollowed-out graphic portions 311a to 311j corresponding to the multiple light units 22 will be shown on the outer shell 10a, 10b, 10c. As a result, the looks of the projecting decoration when turned on and when turned off are significantly different, thereby inciting a sense of surprise and fun and enhancing a decorative effect.

Preferably, the controller 40 has a sound module which produces sounds when the multiple light units 22 are turned on or turned off. The controller 40 simultaneously controls the multiple light units 22 of the light assembly 20 to turn on or turn off and controls the sound module to produce sounds, further enhancing ambience and inciting the sense of fun.

Besides, as shown in FIGS. 8, 9, and 17 to 19, the controller 40 turns on a part of the multiple light units 22 while turning off another part of the multiple light units 22, so that various projected FIGS. 60a to 60i of the multiple hollowed-out graphic portions 311a to 311j corresponding to different light units 22 are shown on the outer shell 10a, 10b, 10c. Since the multiple hollowed-out graphic portions 311a to 311j have different graphics, various projected FIGS. 60a to 60i are shown on the outer shell 10a, 10b, 10c. When the controller 40 repeatedly turns off the originally-turned-on light units 22 while turning on the originally-turned-off light units 22, the outer shell 10a, 10b, 10c will continuously show various projected FIGS. 60a to 60i, similar to animations, thereby inciting the sense of surprise and fun and enhancing the decorative effect.

Additionally, the controller 40 is preset to turn on a part of the multiple light units 22 and to turn off another part of the multiple light units 22. For example, in a lighting configuration of a first embodiment in accordance with the present invention, as shown in FIG. 8, the controller 40 first controls the light unit 22 corresponding to the hollowed-out graphic portion 311a to turn on and controls the light unit 22 corresponding to the hollowed-out graphic portion 311b to turn off, so the projected FIG. 60a corresponding to the hollowed-out graphic portion 311a is shown on the outer shell 10a. Alternatively, in another lighting configuration of the first embodiment, as shown in FIG. 9, the controller 40 controls two of the multiple light units 22 corresponding to the hollowed-out graphic portions 311a, 311b to turn on. That is, two of the multiple light units 22 emit light to two corresponding hollowed-out graphic portions 311a, 311b. When the light passes through the two hollowed-out graphic portions 311a, 311b to be projected to the outer shell 10a, the two projected FIGS. 60a, 60b shown on the outer shell 10a overlap with each other. Therefore, the outer shell 10a shows

the two projected FIGS. 60a, 60b corresponding to the two hollowed-out graphic portions 311a, 311b simultaneously.

Similarly, in a lighting configuration of a second embodiment in accordance with the present invention, as shown in FIGS. 15 to 17, the controller 40 controls the light units 22 corresponding to the hollowed-out graphic portions 311c, 311d, 311e to turn on and controls the light units 22 corresponding to the hollowed-out graphic portions 311f, 311g to turn off. Therefore, the outer shell 10b shows the projected FIGS. 60c, 60d, 60e corresponding to the hollowed-out graphic portions 311c, 311d, 311e. Or, in another lighting configuration of the second embodiment, as shown in FIG. 18, the controller 40 further controls the light units 22 corresponding to the hollowed-out graphic portions 311f, 311g to turn on, so that the outer shell 10b shows the projected FIGS. 60c to 60g corresponding to the hollowed-out graphic portions 311c to 311g. Alternatively, the controller 40 controls the light units 22 corresponding to the hollowed-out graphic portions 311c, 311f, 311g to turn on and controls the light units 22 corresponding to the hollowed-out graphic portions 311d, 311e to turn off. So, the outer shell 10b shows the projected FIGS. 60c, 60f, 60g corresponding to the hollowed-out graphic portions 311c, 311f, 311g, and the projected FIGS. 60c, 60f, 60g do not overlap with each other.

Besides, in a third embodiment of the projecting decoration in accordance with the present invention, as shown in FIG. 19, the controller 40 controls the light units 22 corresponding to the hollowed-out graphic portions 311h, 311i to turn on and controls the light unit 22 corresponding to the hollowed-out graphic portion 311j to turn off. So, the outer shell 10c shows the projected FIGS. 60h, 60i corresponding to the hollowed-out graphic portions 311h, 311i.

Furthermore, as shown in FIGS. 2 and 13, in the first and second embodiments of the projecting decoration, the outer shell 10a, 10b is made of rigid materials and comprises a front shell body 11 and a rear shell body 12. The front shell body 11 and the rear shell body 12 are connected to each other. The light assembly 20 and the light-blocking cover 30 are disposed in the front shell body 11 and the rear shell body 12, respectively. The base board 21 of the light assembly 20 is mounted at the rear shell body 12. The multiple light units 22 emit light toward the front shell body 11. Alternatively, as shown in FIGS. 19 and 20, in the third embodiment of the projecting decoration, the outer shell 10c is made of flexible materials. The projecting decoration comprises a blower 50 connected to the outer shell 10c and blows air into the outer shell 10c such that the outer shell 10c remains three-dimensionally shaped. Regardless that the outer shell 10a, 10b, 10c is made of flexible or rigid materials, the projecting decoration provides higher decorative effect and sense of fun. Therefore, consumers can choose from different embodiments of the projecting decoration based on decorative needs.

Additionally, as shown in FIG. 10, the outer shell 10a, 10b, 10c has at least one painting portion 13 disposed at an external surface of the outer shell 10a, 10b, 10c. The at least one painting portion 13 can be presented on the external surface of the outer shell 10a, 10b, 10c by printing, adhesion, or being one-piece-formed with the outer shell 10a, 10b, 10c. Having the at least one painting portion 13 on the external surface of the outer shell 10a, 10b, 10c can enhance the decorative effect of the projecting decoration. Furthermore, when at least one of the multiple light units 22 emits light toward the corresponding hollowed-out graphic portion 311a to 311j to project the light to the outer shell 10a, 10b, 10c, at least one of the projected FIGS. 60a to 60i on the

outer shell 10a, 10b, 10c and the at least one painting portion 13 overlap with each other. In other words, the at least one painting portion 13 cooperates with the projected FIGS. 60a to 60i of the hollowed-out graphic portion 311a to 311j shown on the outer shell 10a, 10b, 10c when the light unit 22 corresponding to the hollowed-out graphic portion 311a to 311j is turned on, thereby further enhancing the decorative effect and the sense of fun.

To sum up, the light assembly 20 and the light-blocking cover 30 are mounted inside the outer shell 10a, 10b, 10c. The controller 40 controls the multiple light units 22 of the light assembly 20 to emit light. The light passes through the multiple hollowed-out graphic portions 311a to 311j of the light-blocking cover 30 to be projected to the outer shell 10a, 10b, 10c. So, the outer shell 10a, 10b, 10c is lit up and shows the projected FIGS. 60a to 60i. Besides, the controller 40 controls a part of the multiple light units 22 to turn on while controlling another part to turn off, so that the outer shell 10a, 10b, 10c shows different projected FIGS. 60a to 60i of the hollowed-out graphic portions 311a to 311j corresponding to different light unit 22s, thereby enhancing the decorative effect and the sense of surprise and fun.

Even though numerous characteristics and advantages of the present invention have been set forth in the foregoing description, together with details of the structure and features of the invention, the disclosure is illustrative only. Changes may be made in the details, especially in matters of shape, size, and arrangement of parts within the principles of the invention to the full extent indicated by the broad general meaning of the terms in which the appended claims are expressed.

What is claimed is:

1. A projecting decoration comprising:
an outer shell being hollow internally and allowing light to pass through;
a light assembly mounted inside the outer shell and comprising
a base board;
multiple light units mounted at the base board and being controllable to emit light;
a light-blocking cover mounted inside the outer shell, mounted at the base board, and comprising
a light-blocking body being hollow, connected to the base board of the light assembly, and having multiple hollowed-out graphic portions respectively corresponding to the multiple light units;
at least one separating wall mounted inside the light-blocking body and disposed between each adjacent two of the multiple hollowed-out graphic portions;
a controller electrically connected to the light assembly and controlling a part of the multiple light units to turn on and another part of the multiple light units to turn off;
wherein when the controller turns on or off each one of the multiple light units, each one of the multiple light units emits light to a corresponding one of the multiple hollowed-out graphic portions; the light passes through said hollowed-out graphic portion to project to the outer shell, such that a projected figure corresponding to said hollowed-out graphic portion is shown on the outer shell; and
wherein at least two of the projected figures on the outer shell corresponding to at least two of the multiple hollowed-out graphic portions overlap with each other.

2. The projecting decoration as claimed in claim 1, wherein

the light-blocking body has
an assembling opening;
the base board of the light assembly is mounted at the assembling opening of the light-blocking body;
the multiple light units extend into the light-blocking body; and
each adjacent two of the multiple light units are separated by one of the at least one separating wall to separate the lights emitted by the multiple light units.

3. The projecting decoration as claimed in claim 2, wherein the controller has

a sound module producing sounds when the multiple light units are turned on or turned off.

4. The projecting decoration as claimed in claim 3, wherein

the outer shell comprises
a front shell body and a rear shell body connected to each other;
the base board of the light assembly is mounted at the rear shell body; and
the multiple light units emit light toward the front shell body.

5. The projecting decoration as claimed in claim 4, wherein the outer shell has

at least one painting portion disposed at an external surface of the outer shell.

6. The projecting decoration as claimed in claim 5, wherein at least one of the projected figures on the outer shell corresponding to at least one of the multiple hollowed-out graphic portions and the at least one painting portion overlap with each other.

7. The projecting decoration as claimed in claim 3, wherein

the outer shell is made of flexible materials;
the projecting decoration comprises

a blower connected to the outer shell and blowing air into the outer shell such that the outer shell remains three-dimensionally shaped.

8. The projecting decoration as claimed in claim 7, wherein the outer shell has

at least one painting portion disposed at an external surface of the outer shell.

9. The projecting decoration as claimed in claim 8, wherein at least one of the projected figures on the outer shell corresponding to at least one of the multiple hollowed-out graphic portions and the at least one painting portion overlap with each other.

10. The projecting decoration as claimed in claim 1, wherein the controller has

a sound module producing sounds when the multiple light units are turned on or turned off.

11. The projecting decoration as claimed in claim 1, wherein

the outer shell comprises
a front shell body and a rear shell body connected to each other;
the base board of the light assembly is mounted at the rear shell body; and
the multiple light units emit light toward the front shell body.

12. The projecting decoration as claimed in claim 1,
wherein
the outer shell is made of flexible materials;
the projecting decoration comprises
a blower connected to the outer shell and blowing air 5
into the outer shell such that the outer shell remains
three-dimensionally shaped.
13. The projecting decoration as claimed in claim 1,
wherein the outer shell has
at least one painting portion disposed at an external 10
surface of the outer shell.
14. The projecting decoration as claimed in claim 13,
wherein at least one of the projected figures on the outer
shell corresponding to at least one of the multiple hollowed-
out graphic portions and the at least one painting portion 15
overlap with each other.
